GAME

Benjamin F. Wupper, Park Ridge, Ill.

Application March 14, 1932, Serial No. 598,562

15 Claims. (Cl. 273—130)

My invention relates, generally, to games, and more particularly to a form of game board which may be used for playing a number of different games.

5 It is an object of my invention to provide an improved game board which may be utilized in playing any type of game in which each of the players, unknown to the other, selects certain positions on the board which, as an object of the 10 game, are to be discovered by his opponent. The selection referred to may be temporarily registered upon the board, or may be mentally retained by the player, and the salient feature of my invention is the provision of means whereby the 15 opponent may mechanically register his guess as to the selection and whereby the registration made by him will be visible to the other player.

A further object of my invention is to provide an improved game board which, with the utilization of suitable masks, may be used to play a 20 large number of different kinds of games.

A further object of my invention is to provide an improved game board for playing salvo.

A further object is to provide an improved 25 marker for game boards.

A further object is to provide an improved game which is simple in construction, may be economically manufactured, and which will have the quality of maintaining the interest of adults, 30 as well as of children.

Other objects will appear from time to time in the following description, in which reference is made to the accompanying drawings, wherein

Figure 1 is a perspective view of one form of 35 my invention;

Figure 2 is a plan view of the construction shown in Figure 1, a portion of the figure being in section to illustrate the method of supporting the board;

40 Figure 3 is a fragmentary vertical sectional view of the game board;

Figure 4 is a perspective view of a marker used with the board, shown in Figure 1;

45 Figure 5 is an elevational view of a portion of a modified form of my invention;

Figure 6 is a vertical sectional view, taken on the line 6—6 of Figure 5;

50 Figure 7 is a fragmentary horizontal sectional view, taken on the line 7—7 of Figure 5;

Figure 8 is an enlarged fragmentary vertical sectional view of a second modified form of my invention, taken on the line 8—8 of Figure 9;

55 Figure 9 is a fragmentary perspective view of said second modified form;

Figure 10 is a fragmentary elevational view of the game board of Figures 8 and 9;

Figure 11 is a central vertical sectional view of a third modified form of my invention;

Figure 12 is a vertical sectional view thereof, 5 taken on the line 12—12 of Figure 11;

Figure 13 is an enlarged fragmentary vertical sectional view of the board shown in Figure 11;

Figure 14 is a fragmentary plan view of the game board and its support; 10

Figure 15 is an enlarged perspective view of the markers utilized with the game board shown in Figure 11;

Figures 16 and 17 illustrate forms of charts which may be used with the game board illustrat- 15 ed in Figure 11;

Figure 18 is an elevation of a fourth form of my invention;

Figure 19 is an end elevational view of the form shown in Figure 18; 20

Figure 20 is an enlarged elevational view of a piercing pin used in connection with the form of my invention shown in Figures 18 and 19, and

Figure 21 is a plan view of a portion of a mask placed upon the game board of the type illustrated 25 in Figure 11, showing how the latter may be used in playing such games as checkers.

The game board shown in Figures 1 to 4, inclusive, comprises a board 30 which, although referred to as a "board", may be made of materials other than wood such, for example, as a phenol condensation product, or hard rubber, or other suitable composition. The board is provided with two fields of equally spaced holes 32, each comprising 30 ten rows of ten holes each. While, as 35

herein disclosed, all the forms of my invention are provided with fields of this size, the number of holes may, of course, be increased or decreased as may seem desirable. For the purpose of description, the right hand field of one hundred holes is herein designated the "A" field, and the left hand field the "B" field. 40

Above each of these fields are located groups of holes 34, which are used in registering the score. In the game of salvo, for the playing of

which this game board is particularly adapted, the scoring holes above each field comprise a group 36 of four holes, which represent a "battle-ship", a group 38 of three holes, which represent a "cruiser", and two groups 40, 42, each representing a "destroyer". In the drawings, the scoring holes for the battleship, the cruiser and the two destroyers are designated, respectively, 36—A, 38—A, 40—A and 42—A. These scoring fields may be painted in a distinctive color, as 45

indicated in Fig. 1, or may assume the figure of a naval ship, with the holes 34 passing through the hull of the ship. The right hand field A, on each side of the board, is provided with a plurality of horizontal grooves 44, one above each row of holes. Markers 46 (Fig. 4), each comprising a small stamping of sheet steel, sheet celluloid, or similar material, are provided with openings 48 which are considerably larger in diameter than the holes 32, and with an acute angle flange 50. In the embodiment shown, the flanges 50 of the markers 46 are adapted to fit in the grooves 44 rather snugly, so that the marker will lie against the surface of the board. The board 15 may be supported in any suitable way, such, for example, as by a pair of standards 52, each of which has a vertical dovetail groove 54 formed therein to receive the dovetailed lower end portion 56 of the side edges of the board.

20 A plurality of pins 58 are provided for use with the board. The pins are preferably of different, readily distinguishable colors. For the purposes of illustration, I have found it practicable to provide approximately five groups of twenty-five pins each, five groups of eighteen pins each, five groups of ten pins each, and five groups of five pins each, each group of pins being of a different color. Inasmuch as it is rather difficult to obtain twenty different colors, each readily distinguishable from the others, approximately half of the groups may, in addition to their color marking, have an additional distinguishing feature. For example, the groups with the fewer number of pins may be distinguished from the 30 other groups by coloring the ends of the pins white, or, the pins themselves may be made square in cross-section instead of circular. Any other suitable means may be used to differentiate the different groups of pins, and the pins, in addition to being of distinguishable colors, may have additional designating markings. The pins are, preferably, substantially cylindrical in shape and have beveled or rounded ends. They are made sufficiently small in diameter so that they may be 40 readily inserted in the holes 32 and 34, and so that they will practically drop from the board if the latter is shaken while being held in a horizontal position.

The method of playing the game with the apparatus above described is as follows:

The board is placed between the players, in a vertical position, so that each player can see only one side of the board. Each player then places his ships in what he believes to be strategic positions on the field A on his side of the board, by attaching the markers 46 in general as indicated in Fig. 1. Four markers in line represent a battleship, three markers in line a cruiser and two markers in line a destroyer. It is, of course, required that the markers be placed over adjacent holes in the field A, but they may be placed in a horizontal line, a vertical line, or in either diagonal line. Suitable shields, consisting of sheets of cardboard or other material, may be provided to prevent the opponent from watching the player locate his ships by observation through the holes 32 in the field A.

Each player having located his markers in the prescribed manner and the shields having been removed, the playing of the game is conducted in the following manner:

Each player alternately fires seven "salvos" at his opponent's "ships" by inserting seven pins 75 of the same color in any desired holes 32 in the

field B. The players shoot their salvos alternately and when a player has finished firing his salvo, his opponent will report "No hits", if none of the pins has been inserted in a hole over which the opponent has placed a marker; but if the player 5 has struck one of his opponent's ships, his opponent will indicate this fact by inserting a pin of the same color used in the salvo, in the scoring hole 34 of one of the score fields 36, 38, 40, 42, depending upon which ship has been struck. 10

The playing of the game is continued in this manner, each player, in turn, firing a salvo of seven shots at his opponent's hidden ships until a ship has been completely disabled and placed out of action by having a pin placed in each 15 one of the holes over which the markings for the ship are located. Thereafter, the player whose ship has thus been placed out of action no longer has salvos of seven shots each but, instead, his salvos will thereafter consist of a 20 number of shots less than seven—depending upon the type of ship put out of action. Upon having his battleship destroyed the player may, for example, lose three shots; for his cruiser, two shots, and for each of the destroyers, one shot. 25

The game is continued in this manner until all of the ships of one of the players have been "sunk".

Various methods of scoring, which it is believed unnecessary to detail herein, may be employed to increase the interest in the game. 30

While the game has been described as being played on the principles of naval warfare, it may take the form of a "treasure hunt", wherein the markers will represent hidden treasure, instead 35 of battleships, and the insertion of a pin in a hole will represent the uncovering of a certain spot in a possible field in which the treasure may be hidden. The game may also be played as representative of aerial combat or bombing expeditions, or as symbolical of various other incidents. 40

In Fig. 5, I have shown a modified form of the game board in which the board itself is formed of sheet metal and comprises a single sheet 60, 45 having a plurality of rows and files of holes 62 pierced therethrough. The arrangement of the holes 62 may be the same as that shown in Fig. 1. Each of the holes has a cylindrical flange 64 formed by the piercing operation, and a small 50 lug 66 struck upwardly from the flange. The markers comprise rings 68, which may be of metal, celluloid, or any other suitable material, and which may readily be hung over the projecting flanges 64, being prevented from falling 55 therefrom by the lugs 66. The edges of the sheet 60 may have beads or rolls 70 formed thereon to stiffen the sheet 60, and the sheet may be supported by a pair of pedestals 72, which are provided with vertical grooves 74 shaped to receive 60 the beads 70 formed along the lower portion of the vertical edges of the board.

A plurality of pins, as above described with reference to the board shown in Figure 1, are of course provided with this board, and the game may be played in the manner as above described with reference to said figure. 65

In the embodiment shown in Figs. 8, 9 and 10, the holes 76 are formed by the intersections of relatively wide, horizontal grooves 78 cut in one side of the board, and vertical grooves 80 cut in the opposite side of the board 82. In addition to the grooves 78 and 80 relatively shallow, narrow horizontal grooves 84 are provided to receive markers 86, 88. The grooves 84 may slope in- 70 75

wardly, as indicated in Figs. 8 and 9, or may be in a horizontal plane. The markers 88 are provided for use on that side of the board where the field corresponding to field A, of Fig. 1, is provided with the horizontal groove 78, while the markers 88 are provided for use on that side of the board having the vertical grooves 80. Each of the markers may have an arrowhead, or other suitable pointer, to indicate the selected hole. If the grooves 84 are cut in a horizontal plane, instead of in the sloping plane, as shown, the board may be substantially completely formed by two operations on a multiple circular saw.

In Fig. 10, the scoring fields 90 and 92 are shown as marked upon the board and as being provided with drilled scoring holes 94. If desired, however, these holes may likewise be formed by means of horizontal grooves similar to the grooves 78, which extend only a portion of the length of the board.

The board 82 may be supported in any suitable manner such, for example, as by means of pedestals detachably secured to the end edges of the board, as indicated in Fig. 1. The pins 58 may readily be inserted through the holes 76 formed by the intersections of the grooves 78 and 80.

The game board may be used to play the salvo game, as above described, or may be used to play others of the games as mentioned hereinafter. A board constructed in the manner shown in Figs. 8, 9 and 10 has a number of advantages in simplicity of the method of manufacture and in economy of production. It, however, has the disadvantage that two different types of markers are necessary, or at least desirable. A further possible disadvantage is that the board should be reasonably thick so as to provide an adequate support for the pins.

In Figs. 11 to 17, inclusive, I have illustrated one of the preferred embodiments of my invention. In this construction, the board 96 is generally similar to the board 30 except that the fields of perforations A and B are placed immediately adjacent each other, so that the right hand file of holes 32 of the field B is spaced from the left hand file of holes of the field A a distance equal to the horizontal spacing between the other files. The two fields A and B thus, together, form a continuous field of equally spaced perforations, so that the board may be used with greater facility for playing games other than those of the salvo type. Inasmuch as the board 96 is generally similar to the board 30, shown in Fig. 1, similar reference characters have been applied to corresponding parts, and such parts will not again be described in detail.

The board 96 is adapted to form the cover of a box comprising end walls 98, 100, side walls 102, 104, which are secured to each other and to a bottom 106. The walls 104 are preferably made of wood, while the bottom 106 may be made of wood or cardboard, or other suitable material. The sides 102, 104 and the end 100 are each provided with rabbets 108 to receive the board 96. When in use, the board 96 is supported by a pair of brackets 110, the bifurcated lower ends of which are pivoted to blocks 112 by means of a pin or pair of nails 114. The block of wood 112 may be glued and/or nailed to the end walls 98, 100 of the box. The upper portions of the brackets 110 are formed to provide a channel 116 (Fig. 14), adapted to receive the board 96. A pair of offset flanges 118 are provided on each of the brackets 110, to form guides and supports

for charts 120, as hereinafter to be described. The brackets have inwardly struck lugs 122 formed to close the lower end of the channel portions of the bracket, and serve as a support for the board 96. When not in use, the brackets 5 may be swung downwardly into the position shown in dotted lines in Fig. 11, and their upward swinging movement is limited by abutment of the lower portion of the bracket with the adjacent end wall of the box. If desired, one 10 or more partitions 124 may be provided for use in segregating the different groups of the pins used in playing the game.

The field A of the board 96 is provided with shallow grooves 126, which lie in a horizontal 15 plane, one groove above each row of holes 32 in the board. The grooves are cut in a horizontal plane, rather than in the sloping plane indicated in the embodiment shown in Fig. 1, in order to reduce the cost of production. 20

With the horizontal groove, it is desirable to provide a marker 128, as shown in Fig. 15, which has some resilient means to aid in holding the marker in the groove. The marker 128 is provided with a rearwardly extending flange 25 130, which has a hump or upwardly bent portion 132. The marker is made from sufficiently resilient material so that the flange 130 thereof may be snapped into a groove 126 and will be retained therein because of the resilient engagement of the lower surface of the flange 130 with the lower surface of the groove, and the engagement of the hump 132 with the upper surface of the groove. The marker 128 is, of course, provided with a large opening 134, which may 30 readily be placed over one of the holes 32, in a position such that the marker will not be visible from the opposite side of the board.

The game board shown in Figs. 11 to 14 may be utilized in the same manner as the board 40 shown in Fig. 1. In using this board, the pins may conveniently be retained in the box, and pins of the proper color selected therefrom during the playing of the game. When the game is not in use, the brackets 110 may, of course, be 45 folded inwardly so as to lie within the box, and the board slid in the rabbets 108 so as to form a cover for the box. When in use, the box, of course, forms a very stable support for the board.

The board shown in Fig. 11 may be used for a 50 large variety of games in addition to those of the type previously described, by the use of various masks, such as shown in Figs. 16, 17 and 21. For example, an educational game may be played by utilizing charts 136, 138, shown in 55 Figs. 16 and 17, respectively.

These charts are substantially the same size and shape as the board 96 and are adapted to be placed one upon each side of the board, and accurately positioned relative thereto by means of a 60 pin 140 (Fig. 14) passing through holes 142, 144 formed in the corners of the sheets 136, 138, respectively. The charts are held so as to lie closely adjacent the board 96 by the flanges 118 which form part of the brackets 110. 65

The charts 136, 138, shown in the drawings, are illustrated as for the purpose of teaching geography, more particularly the capitals of the various States of the United States of America. Similar sets of charts may, of course, be provided 70 for teaching any other desired branch of knowledge, such as arithmetic, literature, history and other various exact and natural sciences.

The charts will be furnished in sets, each chart being ruled off into squares 146, 147, 148, and 149, 75

150 and 151, each having a central perforation 152, of slightly larger diameter than the diameter of the holes 32 in the board 96. Each of the charts 136 has questions printed in half of the squares, 5 and answers printed in the other half. The charts are provided in sets, such as chart 136, designated "Chart 1—A", and the chart 138, designated "Chart 1—B".

When these charts are properly positioned on 10 opposite sides of the board 96, the square containing the answer to a question will lie directly in line with the square on the other chart upon which the question is printed. For example, a square 146 contains the question, "What is the 15 capital of Georgia?"—and the square 149, which will be directly behind the square 146 when the charts 136 and 138 are properly positioned over the board 96, has the answer "Atlanta" printed thereon. Similarly, square 150 contains the 20 answer to the question in square 147, and square 151 contains the answer to the question in square 148.

Having properly positioned a set of charts on the game board, the game is played in the following manner: Each player is provided with any desired equal number of pins. For example, each player may be provided with twenty pins. The play is commenced by one player reading a question from the board. His opponent will examine 30 the squares containing the answers, and insert one of his pins in the aperture 32 in the square in which is printed what he believes to be the correct answer to the given question. The pin is pushed through the board 96 and through the chart on the opposite side. If the pin is projected into the square which contained the question which was asked, the player who asked the question pushes the pin back to his opponent. If the pin is inserted in the wrong hole, the player who asked the 40 question withdraws the pin and retains it. The game is, of course, won by the player who first succeeds in obtaining the twenty pins from his opponent.

If desired, the box may be mounted on a 45 swivel at its center, so that it and the board may be readily turned through an angle of 180° and thus permit the players to verify the correctness of their respective decisions as to which player is to receive the pin. The charts may have the 50 questions and answers printed on both sides thereof, so as to increase the repertoire. By providing a dozen or so of sets of charts, a large range of useful information may be represented, and the player of the game will thus acquire a wide knowledge of useful facts.

The board 96 may also be utilized in playing a large number of other games similar to that played by means of the charts shown in Figs. 16 and 17. It may also be utilized in playing other games, of 60 the type in which a counter is moved over designated spaces, such as the game of checkers; games of the type in which a counter travels along a designated graduated path, in accordance with the throw of dice, or the indications of a spinner having a number scale; or games of the peg and board type, in which pegs are inserted in holes formed in a board, either to mark the score or in actual playing of the game, such as cribbage, or a game in which the players alternately 65 insert a peg in any desired hole, the object of each player being to place his pin so as to have five pins in a horizontal, vertical, or diagonal line. In most of these games, it will be found desirable to place a mask over the board 96. For example, 70 in Fig. 21, I have illustrated a mask 154 placed

over the board 96, and held in registry therewith by a plurality of pins 156 (one only shown, in Fig. 21) inserted in alignment holes 158 formed in the mask. The mask 154 is illustrated for the playing of the game of checkers, and is accordingly marked with checkerboard squares, each square having a perforation slightly larger than the hole 32 of the board 96 lying beneath it. By providing a plurality of masks with a given board, the board may readily be utilized for playing a 10 very large number of different games. A single, inexpensive mask formed of a sheet of stiff paper may be marked so as to make it possible to utilize it in playing several different games. It will be apparent to those skilled in the art that there 15 are a large number of different possible forms of masks which could be provided for use in playing games at present known.

In Fig. 18, I have shown a device particularly adapted for playing games of the salvo type, 20 which comprises three plates 160, 162 and 164, which are pivotally joined at their upper edges by means of hinges 166, and the lower edges of which may be clamped together by means of a pair of cam surfaced clamps 168, which are rotatably secured to the lugs 170 formed on the plate 164, and the cam surfaces of which are adapted to engage the lower edge of the plate 160 to clamp the lower edges of the three plates firmly together by manual rotation of the cam surfaced 30 clamp 168.

Each of the plates has a pair of large square openings 172, 174, formed therein, and two sets of openings 176, which may be used for scoring purposes. The central plate 162 is provided with a 35 pair of fixed dowel pins 178, which project sufficiently from the surface thereof to form supports for a pair of sheets 180. The sheets 180 each have printed thereon two fields of one hundred squares each, which, when the sheet is properly 40 positioned between the plates, will lie respectively behind the openings 172 and 174. The sheet also has printed thereon markings to designate squares observable through the scoring openings 176. The opposed surfaces of the plates 160, 45 162 and 164, are preferably serrated, or otherwise roughened, or may have a thin coating of rubber applied thereto so as to firmly engage and hold the edges of the sheet of paper when the three plates are clamped together. 50

To aid in securing a tight clamping action, the plates 160 and 164 are preferably sprung slightly, as indicated in dotted lines in Fig. 19, so that when the plates are drawn tightly together by means of the clamp 168, the plates will firmly 55 clamp the paper along the entire edge of the latter.

With this game are provided a plurality of piercing pins 182 (Fig. 20), groups of which, as in the embodiment of Fig. 1, are colored distinctively. The game is played in the following manner: Each player takes a blank form sheet 184 and positions his various ships thereon by marking the chart in any suitable manner, as by drawing small squares 186 within the squares 65 printed on the sheet. After each of the players has thus "located" his ships, the sheets 184 are inserted between the plates 160 and 162, and 164 and 162, respectively, and the frame plates 160, 162 and 164 firmly forced together by means of 70 the clamp 168. Thereafter, each player selects seven pins 182, of a common color, and the players alternately "fire" their salvos, as above described, by piercing both sheets 184 with the pointed pins 182, until one of the player's ships 75

has been "sunk". Hits are, of course, registered in the scoring openings 176, as will be readily understood.

The apparatus shown in Figs. 18 and 19 is not 5 illustrated as being provided with means for supporting the plates. Any suitable means are, of course, provided so that the board may be supported in a vertical plane between the two players. If desired, the apparatus of Figs. 18 and 19 may 10 be constructed so that it is unnecessary to use printed forms. This may be done by providing a grille with a hundred squares, or other suitably shaped openings, in place of each of the large openings 172, and separating the scoring openings 15 176 with suitable division means. The central plate 162 is provided to separate the sheets 184 so that the markings on a player's sheets 184 will not be visible to his opponent by transmitted light. If a sufficiently opaque paper is used, a single sheet 20 may be clamped between two plates, such as 160 and 164, and thus the central plate 162 may be omitted.

In the embodiments shown in Figs. 1 to 14, the 25 field A on each side of the boards may be colored black, so as to form a "blackboard" upon which the location of the ships may be marked by means of chalk. This marking will, of course, be in lieu of the use of the markers 46, 68, 86, 88, and 128.

Various other modifications may be made in 30 the construction of the game and its various parts, and in the materials of which the various parts are made, without departing from the salient features of my invention. It will therefore be understood that while I have shown but a few 35 embodiments of my invention, it may be embodied in a large variety of different forms, all coming within the scope of the claims which follow.

I claim:

1. In combination, a box, a game board in the 40 form of a cover for said box, and a pair of supports for said cover pivoted on said box and arranged to be folded within the latter.

2. In combination, a game board having a 45 plurality of spaced holes therein, pins adapted to be inserted in said holes, a mask shaped to cover certain of the holes in said board and having perforations registerable with others of the holes in said board, and means detachably to hold said mask in a predetermined position on 50 said board.

3. In combination, a game board having a 55 plurality of spaced holes extending therethrough, a pair of charts having perforations spaced to be registerable with holes in said board, means for holding said charts one on each side of said board with the perforations of the former in registry with the holes of the latter, indicia on said charts adjacent each of the perforations thereof, the indicia on one chart bearing a predetermined 60 relationship to the indicia on the other chart, and a plurality of pins insertable in said holes so as to be visible from both sides of said board.

4. In combination, a game board having a 65 plurality of perforations, means to support said board in a vertical position, a plurality of indicia positioned adjacent the perforations in said board on both sides thereof, the indicia on one side bearing a predetermined relationship to the indicia on the opposite side thereof, and pins insertable in said 70 holes to designate selected indicia.

5. In combination, a metal sheet having a 75 plurality of perforations formed therein, an annular flange surrounding each of said perforations, means for supporting said sheet in a vertical position between two opposing players, markers

arranged to designate selected ones of said perforations arranged to be supported by said flanges so as to be visible from one side only of said sheet, and a plurality of pins insertable in said perforations.

6. In a game apparatus, the combination of a 5 perforated board, means to support said board in a vertical position, apertured means to indicate selected perforations of said board, said apertured means being visible from one side only of said 10 board, and a plurality of groups of distinguishable pins insertable in said board to designate selected perforations thereof.

7. A marker adapted to be detachably secured 15 to a game board having a groove in the surface thereof, comprising a unitary piece of resilient sheet material thinner than the groove in the board with which it is to be used, said marker having a portion corrugated and insertable in the groove of the board.

8. In combination, a board having a plurality 20 of holes formed therein in rows and files equidistantly spaced and having a plurality of grooves one adjacent each row of holes, a plurality of perforated markers each having a flange engageable 25 in one of said grooves, the perforations in said markers being of greater diameter than the holes in said board, and a plurality of groups of pins insertable in the holes in said board from either side of the latter, each pin of a group having a characteristic by which it may be distinguished from pins of the other groups, and means for supporting said board in a vertical plane whereby players on opposite sides thereof may readily attach said 30 markers and insert said pins.

9. In game apparatus an apertured board 35 adapted to be vertically positioned between opposing players so that one side only thereof is visible to each of the players, and providing a plurality of playing fields complementarily disposed on opposite faces of said board, and a plurality of pins insertable in the apertures so that each will have a portion visible from both sides of the board, said playing fields comprising a plurality of pairs of fields, each of said fields bearing 40 indicia individual to the apertures in the board, and the indicia upon one of the fields being unlike the indicia upon the other of said pair of fields, one of said fields being disposed on one 45 side of said board and the other of said fields being disposed on the other side of said board, with the indicia of one field bearing a predetermined relation to the indicia upon its opposed field.

10. In a game of the character described, a 50 playing board having a playing surface divided into two corresponding playing areas, said areas having corresponding series of openings in the playing surface, apertured target members, means for holding said target members on one of said playing areas with the apertures thereof in register with any selected ones of said openings respectively, and playing pieces adapted for insertion through said aperture and into said openings to indicate plays made.

11. A game board adapted to be positioned upright between two players and provided with two groups of perforations, enclosure means for designating a series of the perforations in one of said groups on each face of the board and arbitrarily positioned by each player for providing an 55 unseen target for the opponent, and a plurality of pins adapted to be inserted through the perforations from opposite sides of the board in the playing of the game.

12. A game board adapted to be positioned up- 70 75

- right between two players and provided with a plurality of perforations, enclosure means on each face of the board and arbitrarily positioned by the respective players to designate a series of perforations serving as an unseen target for the opponent and a plurality of pins adapted to be inserted through the perforations from opposite sides of the board in the playing of the game.
13. A game board adapted to be positioned upright between two players and provided with two groups of perforations, enclosure means for designating a series of the perforations in one of said groups on each face of the board and arbitrarily positioned by each player for providing an unseen target for the opponent, and a plurality of pins differentiated one from another and adapted to be inserted through the perforations from opposite sides of the board in the playing of the game.
14. A game board adapted to be positioned upright between two players and provided with two

groups of perforations, enclosure means for designating a series of the perforations in one of said groups on each face of the board and arbitrarily positioned by each player for providing an unseen target for the opponent, and a plurality of pins differentiated in groups and adapted to be inserted through the perforations from opposite sides of the board in the playing of the game.

15. In a game of the character described, a playing board having a playing surface divided into two similar playing areas, said areas having corresponding series of pin receptacles in the playing surface, separable target members, means for supporting same on said board to indicate selected receptacles thereof and to be visible to only one of a pair of players facing each other with the board located between them, and playing pieces adapted for insertion in said receptacles so as to be visible to both players and to indicate to them the plays made.
